PACKAGING TRAY FOR COOKIES OR THE LIKE

Hugh R. Weiss, Montclair, N.J., assignor to The Pantasote Company, Passaic, N.J., a corporation of
New Jersey

Filed Nov. 19, 1962, Ser. No. 72,539

Term of patent 14 years

(Cl. D58—11)

I claim:

The ornamental design for a packaging tray for cookies or the like, as shown.
